United States Patent Office.

JOHN P. SMUCKER, OF ASHLAND, ASSIGNOR TO HIMSELF, AND
RUSSEL S. OWEN, OF BRYAN, OHIO.

Letters Patent No. 94,252, dated August 31, 1869.

IMPROVEMENT IN HUSK-MAT.

The Schedule referred to in these Letters Patent and making part of the same

To all whom it may concern:

Be it known that I, JOHN P. SMUCKER, of Ashland, in the county of Ashland, and State of Ohio, have invented a new and useful Improvement in Husk-Mats; and I do declare that the following is a true and accurate description thereof, reference being had to the accompanying drawings, and to the letters of reference marked thereon, and being a part of this specification.

Figure 1 is a perspective view of my invention, from the top.

Figure 2 is a vertical section on the line X X in fig. 1.

Like letters refer to like parts in each figure.

The nature of this invention relates to the construction and manufacture of floor-mats, and consists in making them from corn-husks, or other similar material, secured in and through a metallic-sheet base, in a new and novel manner, as more fully hereinafter described.

In the drawings—

A represents a sheet-metal base, of any desired size, shape, and form. This base is perforated, at intervals of about half an inch apart, in each direction, with square holes, the instrument with which the perforations are made being of such a peculiar shape as to commence cutting in the centre, and outwardly toward each course of the perforations, in such a manner that there will be turned downward a lip, a, upon each side of the square of the perforation, each lip being tri-

angular in shape, with its base forming one side of the perforation.

Tufts of husks are then taken, folded in the centre of their lengths, and the folds then presented to and inserted through the perforations from the top of the metallic base, until all said perforations are filled, taking care that the folds below the base shall be all on the same plane, and of equal length below said base. The lips a may then, by means of a clamp or vise, be made to clasp and hold the tufts in place securely, while the folds serve as feet b to the mat.

The upper part of the husks may be trimmed off to any uniform length desired.

The husks may be colored, and so marked as to present a pleasing variety of figures on the face of the mat.

I do not confine myself strictly to a sheet-metal base, as described, for a wooden base may be used, by employing some suitable device to hold the tufts in place.

What I claim as my invention, and desire to secure by Letters Patent, is—

As a new article of manufacture, Husk-mats, constructed substantially as herein described, with a metallic or wooden base, A, as set forth.

JOHN P. SMUCKER.
